UNITED STATES PATENT OFFICE.

DAVID G. WYETH, OF NEWARK, OHIO, ASSIGNOR TO AUGUSTUS G. WYETH
AND WILLIAM M. MCCULLY, OF SAME PLACE.

SLEIGH.

SPECIFICATION forming part of Letters Patent No. 444,405, dated January 6, 1891.

Application filed December 5, 1889. Serial No. 332,718. (No model.)

To all whom it may concern:

Be it known that I, DAVID G. WYETH, a citizen of the United States, residing at Newark, in the county of Licking and State of Ohio, have invented new and useful Improvements in Sleds, Sleighs, and Sleigh-Runner Attachments for Wheeled Vehicles, of which the following is a specification.

My invention relates to improvements in sleds, sleighs, and sleigh-runner attachments for wheeled vehicles wherein wood-rave, runner, and knees are used; and the object of my improvement is to enable the frame-work of the sled, sleigh, or sleigh-runner attachment to be made by putting together the same with the usual wood-rave, runner, and knees, but with unmortised and untenoned joints of knees and rave and knees and runner, such joints and the frame-work of such knees, runner, and rave being secured strongly and rigidly together by iron side and T-plates. I attain these ends by the mechanism illustrated in the accompanying drawings, like lettering referring to like parts.

Figure 1 is a perspective view of one bob or runner or side of a sled or sleigh, having thereon iron side or frame plates and T-plates. Fig. 2 shows one of the side plates removed. Fig. 3 shows a T-plate removed.

As shown in Fig. 1, the frame of the sled or runner is made up of a rave *a*, runner *b*, and two knees *c c'*. The knees *c c'* are cut to fit against the rave *a* and runner *b* at proper angles and no mortise-and-tenon joints are used.

Upon either side of the unmortised and untenoned joints of knees *c c'* and rave *a* are placed side plates *d d d d*, which are secured together by appropriate rivets, screws, or bolts passing into or through the wood-work. One of these side plates is shown detached in Fig. 2. It may be conveniently made of malleable iron cast, and has two flanges *e e*, adapted to clasp or clinch down upon the knees *c c'*.

The form of any such side plate *d* is varied, 45 accordingly as it is to be used at front or rear knee and upon the inside or outside.

Upon either side of the unmortised and untenoned joints of knees *c c'* and runner *b* are placed T-plates *g g g g*, which are secured 50 together by appropriate rivets, screws, or bolts passing into or through the same and the wood-work. One of these T-plates is shown detached in Fig. 3. It may be made of malleable cast-iron, and has two flanges *h h*, 55 adapted to clasp or clinch down upon the knees *c c'*. The form of such T-plate varies accordingly, as it is to be used at the front or rear joint and on the inside or outside thereof.

In a bob-sled a right and left bob, constituting a pair, are secured together by a proper beam-crossing secured to the rave of each bob in the usual manner. Four bobs enter into the construction of a complete bob-sled or double bob-sled. When the bob or runner is 65 to be used as a sleigh-runner attachment for wheeled vehicles, a box or thimble covering for the vehicle-spindle will be secured to the rave *a* by methods already in use. In an ordinary long sled two or more beams or bolsters 70 are used in the usual manner.

Having thus described my invention, what I claim as new, and desire to secure by Letters Patent, is as follows:

In sleighs, sleds, and sleigh-runner attachments for wheeled vehicles, the combination of two knees *c c'*, with rave *a* and runner *b*, with unmortised and untenoned joints of said knees and runner and rave, the four side plates *d*, and four T-plates *g*, each of said 80 side plates having two flanges *e*, and each of said T-plates having two flanges *h*, all combined and arranged as substantially set forth.

DAVID G. WYETH.
